McCarthy

[57] CLAIM

The ornamental design for a data collection terminal, substantially as shown and described.

DESCRIPTION

FIG. 1 is a side elevation of a data collection terminal showing my new design;

FIG. 2 is a top plan view thereof;

FIG. 3 is an elevation as seen from the side opposite FIG. 1;

FIG. 4 is a front elevation thereof;

FIG. 5 is a bottom plan view thereof; and

FIG. 6 is a rear elevation thereof.
